UNITED STATES PATENT OFFICE.

HERBERT E. FLETCHER, OF LYNN, MASSACHUSETTS.

VALVE CHUCK.

Application filed January 30, 1922. Serial No. 532,932.

To all whom it may concern:

Be it known that I, HERBERT E. FLETCHER, a citizen of the United States of America, residing at Lynn, in the county of Essex 5 and State of Massachusetts, have invented certain new and useful Improvements in Valve Chucks; and I do hereby declare that the following is a full, clear, concise, and exact description of the same, such as will 10 enable others skilled in the art to which it appertains to make and use the same.

This application is a continuation in part of my copending application, Serial Number 404,463, filed August 18, 1920.

15 The present invention relates particularly to valve stem holding chucks, adapted to be used with the type of valve grinding machine described in my copending application hereinbefore referred to, but its use is 20 not limited specifically to such.

The primary object of the invention is to provide a valve chuck which may be easily and readily adjusted so that the face of the valve to be ground may at all times be retained in proper position.

An additional object is to provide a chuck of this character having means to center and maintain the inner end of a valve stem in alignment with the chuck jaws at all times.

30 A further object is to provide a chuck of the character mentioned so constructed as to allow a greater degree of movement of the chuck jaws than is usual in the art, permitting its adaptability to valve stems of 35 any size, without changing.

With these and such other objects in view as will be apparent from the following description, my invention resides in the novel features of construction, combination and 40 arrangement of parts hereinafter described and claimed, and illustrated in the accompanying drawings.

In the drawings:

Figure 1 is a side elevation of the chuck, 45 mounted;

Figure 2 is a horizontal section on line 2—2 of Figure 1;

Figure 3 is a vertical section on line 3—3 of Figure 2;

50 Figure 4 is an elevation of the chuck jaw spindle; and,

Figure 5 is an end elevation of the jaws.

In detail, the chuck comprises a circular base member 1, adapted to be pivotally mounted on a support 2, forming part of a 55 grinding machine, in this instance. A pair

of arms 3, integral with the base, extend upwardly therefrom and carry on their upper ends an integral sleeve 4, forming a bearing for the chuck proper. The base 1, arms 3 and sleeve 4, form in effect a holder which may be rotated on the support 2 over the support stem 5 extending therefrom and threaded at its upper end to receive a nut 6 whereby the base 1 may be clamped in any desired position, the position being regulated by means of graduations 7 on the periphery of the base member.

The sleeve 4 is formed at one end with a depending arm 8 carrying a bearing 9 on the lower end thereof in which is journalled a shaft 10 connected with suitable driving mechanism (not shown) and carrying at its end, a pulley 11 for a purpose hereinafter described.

Rotatably mounted in the sleeve 4, is a hollow cylindrical chuck spindle 12 extending beyond the ends of the sleeve and provided at one end with an enlarged head 13. The opposite end of the spindle has secured thereto in any suitable manner, a pulley 14 disposed above the pulley 11 so that the spindle may be rotated through the medium of driving connection (not shown) between the pulleys. Lubricating cups 15 are provided at the top of the sleeve 4.

As a means of locking the chuck spindle against rotation, I provide a slotted bolt 16 secured on the sleeve 4 by retaining screws 17. The locking bolt is slid longitudinally of the sleeve by means of a handle 18, and is formed at one end with a tongue 19 adapted to engage in any of a series of circumferentially spaced sockets 20 on the inner face of the pulley 14.

Arranged within the spindle 12 is a tube 21 having the split jaws 22 formed along the greater portion thereof, the slots between the jaws being of relatively large width to allow considerable degree of jaw movement. 100 The jaws project in enlarged heads 23 beyond one end of the spindle, and at the opposite end the tube projects beyond the spindle and pulley 14 terminating in a threaded portion on which is received a hand wheel 24 by manipulation of which the tube may be moved longitudinally to expand or contract the jaws 22. The heads 23 of the jaws are of conical configuration and are adapted to slide in a corresponding recess in the head 13. This tube 21 is splined to the spindle 12 by a key 21' so that the tube may move

longitudinally of said spindle but is held to rotate therewith, a splineway 22' being provided in the tube 21 to receive said key. Slidably mounted within the tube is a block 5 25 and arranged between the block and the hand wheel, is an expansion spring 26. The jaw end of the block 25 is provided with a conical socket 27 to receive and center the end of a valve stem 28 held in the chuck 10 jaws. It will be seen that the chuck thus consists of a spindle having a draw-in collet. In operation, a valve stem is inserted in the chuck jaws and centered in the socket of the spring tensioned block 25. The hand 15 wheel 24 is then operated to bring the jaws into gripping engagement with the stem, and the jaws being held in frictional engagement against the spindle head 13, the valve will be rotated on rotation of the spindle, 20 as described.

While I have described certain elements entering into the construction and operation of the preferred embodiment of my invention, I desire it to be understood that I do 25 not limit myself to these, but that any such may be used as will fall within the scope of the invention, as claimed.

I claim:

A chuck of the character described including a sleeve having squared ends, a tubular chuck spindle having a body journalled in said sleeve and projecting at each end therefrom, the forward end of said body being shouldered to bear against the forward squared end of the sleeve, a belt pulley 30 mounted on the rear end of said body and fixed thereto, said belt pulley engaging the rear squared end of the sleeve to hold the spindle therein, a tubular draw-in collet mounted within the spindle for longitudinal 40 movement and splined thereto, the rear end of said draw-in collet being threaded and projecting from the spindle, a plunger slideable in said collet, a spring having one end bearing against the plunger, and a hand wheel screwed on the threaded collet end and bearing against the rear end of the spindle, said hand wheel serving to close the rear end of the tubular collet and forming a bearing for the other end of said spring. 45

In witness whereof I have hereunto set my hand.

HERBERT E. FLETCHER.
